UNITED STATES PATENT OFFICE.

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed April 28, 1921, Serial No. 465,101. Renewed January 25, 1926.

The present invention relates in general to automatic telephone systems, but more especially to such automatic systems as include private automatic exchanges; and the object of the invention, broadly stated, is the provision of novel arrangements in a system of the above character whereby a toll operator in a main exchange or toll office can interconnect toll lines terminating at her position with subscribers' lines which terminate in the private automatic exchanges.

In my prior application, Serial No. 389,633, filed June 17, 1920, which became Patent No. 1,604,372 dated Oct. 26, 1926, I have shown and described a system of the same general type, in which a private branch exchange trunking system is provided comprising, in the case of any particular private automatic exchange, a group of trunk lines which is accessible to the toll operator through the outgoing toll service trunks, and which is also accessible to the main exchange subscribers through the regular exchange trunking system. The trunk lines in this group, since they must provide for two radically different classes of service, are somewhat complicated and expensive to install and maintain. The present invention may be considered to be an improvement on the system shown in the application referred to and was conceived with the object in mind of providing a simpler and cheaper construction, which under certain circumstances would be better adapted to commercial use. In carrying out this object the regular local traffic and the long distance or toll traffic to the private automatic exchange are kept separate to a great extent instead of being handled over a single group of combination trunk lines. A relatively large group of trunks is provided for the regular local calls between the main and branch exchange subscribers, and a separate and much smaller group of trunks is provided for handling the toll connections to the private branch subscribers. Thus the trunk line in each group since they are used for only one class of calls are comparatively simple.

The invention goes further than this, however, and, by a special arrangement in which the regular trunk lines are made available for use in emergencies in handling toll traffic, although on a slightly less efficient basis from a transmission standpoint, the number of toll trunks required in a given case is re-

duced much below the number that would otherwise be necessary. According to this feature of the invention the toll second selectors (such as transmission selector E, Fig. 3) have access to a small group of toll trunks on the particular level assigned to the private automatic exchange to which these trunks extend, the toll trunks being terminated in the first few contact sets of such level so as to give them the preference; and these toll selectors also have access to a certain number of the regular main to branch exchange trunk lines, which are terminated in the remaining sets of contacts in the level in question, and which are taken for use in toll connections therefore only when the regular toll trunks are busy. The exact number of trunk lines to each group in any given case will of course depend on the amount of traffic, but where the size of the private automatic exchange does not exceed 100 lines it is intended to provide only a single toll trunk line under normal conditions, and the system described herein is so illustrated.

The foregoing sets forth in a general way the object and scope of the invention. There are a number of minor features necessarily involved which are not now specifically mentioned, but which together with the broad features outlined above will be fully explained hereinafter with reference to the accompanying drawings.

For a proper understanding of the drawings, Figs. 1-5, inclusive, should be arranged in order with the corresponding lines at the ends thereof in alignment, and when so disposed there is shown a complete circuit connection from a calling toll operator's position in a main exchange or toll office to a called subscriber in a private automatic exchange, together with certain other equipment which is included in the drawing in order to facilitate the explanation of the complete system. The apparatus shown in Fig. 1 is located partly in the toll office, which may or may not be at the same point as the main exchange, and partly in the main exchange. The apparatus shown in Figs. 2 and 3 is also in the main exchange, while the apparatus shown in Figs. 4 and 5 is located in the private automatic exchange.

Referring now to Fig. 1, the toll operator's cord circuit O is a cord circuit of standard type which is used for connecting toll lines with the toll operator's outgoing

toll service trunks. The essential features of the cord circuit will be pointed out and explained in the course of the explanation of the operation of the system. No toll line is shown since it is considered unnecessary in view of the well known and simple character of such circuits, but one of the outgoing toll service trunks is shown extending from the jack J to the toll first selector D. This selector switch is of the ordinary Strowger vertical and rotary type and is operated according to the well known two wire system of control, as is shown and described in the patent to Jacobsen No. 1,349,381, granted Aug. 10, 1920. In view of the fact that a selector of this type is old and well known the switch has been indicated by a dotted rectangle and the circuits are not shown.

The toll first selectors have access to a number of groups of trunk lines, the trunk lines of each group extending to toll second selector's (the so called transmission selectors) by way of associated relay groups. One of these trunk lines is shown extending from the contact set comprising bank contacts 26-28, inclusive, by way of the relay group RG, Fig. 2, to the transmission selector E, Fig. 3. The relay group RG is individual to the transmission selector E and would ordinarily be incorporated in the same switch structure with the selector were it not for the fact that the large number of relays makes it advisable to mount certain of these on a separate base. The transmission selector E is a vertical and rotary selector switch of the type described in the patent previously mentioned.

As will be understood from the general explanation already given, the transmission selector E has access, at a certain designated level, to a toll trunk line extending to the private automatic exchange under consideration. This toll trunk line is indicated by the reference character X, and extends from the bank contacts 134 and 137 in the bank of the toll transmission selector E by way of certain key and relay equipment in the attendant's cabinet at the private automatic exchange, Fig. 4, to the incoming connector H', Fig. 5. The equipment at the attendant's cabinet, as it is commonly called, has been designed especially for use in connection with a toll trunk of this type and the operation of all the apparatus will be described in detail. The incoming connector H' is a Strowger vertical and rotary switch of the usual mechanical construction. The circuits are shown in full and will be described.

The transmission selector E not only has access to the toll trunk X, but also has access to the regular main to branch exchange trunk lines which are used for setting up ordinary connections. One of the trunk

lines in this group is indicated by the reference character Z and extends from the bank contact set comprising bank contacts 150-152, inclusive, located in the bank of a second selector of the regular main exchange 70 trunking system, by way of the repeater F, Fig. 3, and the key and relay equipment at the attendant's cabinet in the branch exchange, Fig. 4, to the incoming connector H, Fig. 5. The repeater F serves to provide 75 a holding circuit for any second selector which connects with the associated trunk line and is used primarily to avoid the necessity of having three conductors in the trunk line extending to the branch exchange. The 80 apparatus at the attendant's cabinet, Fig. 4, which is associated with the trunk line Z is of a general type which has been already used to a considerable extent, the essential 85 features of which are shown and described in the U. S. patent to Powell, No. 1,356,010 granted Oct. 19, 1920. The incoming connector H is, like the incoming connector H', of the ordinary Strowger vertical and rotary 90 type and its operation will be described hereinafter.

The incoming connector H', in which the toll trunk line is terminated, and the incoming connectors in which the regular main to branch exchange trunk lines are 95 terminated, such as the incoming connector H, have common access to all the lines in the private automatic exchange. One of these lines is the line extending to substation A which is an ordinary automatic substation of the usual type, having the calling device S² for the purpose of controlling the automatic switches.

The line switch C is individual to the line of substation A and is a rotary switch of 105 the well known type in which the wipers have no normal position and move in a forward direction only. The function of the line switch C is to extend the associated line when calling to a trunk line leading to an idle selector connector, which is used for completing local connections and also for connecting with the trunk lines extending to the main exchange. In view of the fact that selector connectors of the type mentioned are well known none of these switches are shown herein, but reference is made to the patent to Ray et al., No. 1,468,078, issued Sept. 18, 1923, which shows a selector connector suitable for use in the present 115 situation.

The trunk lines to which the selector connectors in the branch exchange have access are the same trunk lines hereinbefore mentioned as being provided for handling regular main to branch exchange traffic, one of 125 which is the trunk line Z, and it will be understood then that these trunk lines are two way trunk lines. The set of bank contacts comprising contacts 200-202, inclusive, in 130

the upper left hand corner of Fig. 5, are located in the bank of one of the local selector connectors. When the trunk line is taken for use by a selector connector in the branch 5 exchange connection is extended thereto by way of these bank contacts or a multiple thereof, and the line switch C', Fig. 3, at the main exchange end of the trunk line is operated to extend the connection to an idle 10 first selector in the main exchange. The line switch C' it may be stated is similar in construction to the line switch C.

It is thought that the apparatus, having been described more or less in general, will 15 be better understood when described in connection with a detailed description of its operation. For this purpose it will be assumed that the toll operator receives a ticket calling for a connection between the 20 subscriber at substation A and some other subscriber, who may be in a distant city. Any approved method of calling the distant subscriber may be used and accordingly it will not be explained in the present description, 25 and we shall concern ourselves only with the establishing of the connection to the substation A. To make such a call, the toll operator inserts the plug of an idle cord circuit, the plug P' of cord circuit O for example, 30 into the jack of an outgoing toll service trunk, the jack J for example. Assuming that she does as above noted, the line and release relays (not shown) of the selector D immediately energize and the latter prepares 35 the switch for operation in the usual manner. The circuit of the line relay of the said selector includes conductor 21, the upper right winding of the repeating coil associated with the cord circuit, polarized relay 10, the lower 40 right winding of the said repeating coil, and conductor 22. The flow of current in this case through the polarized relay 10 is not in such a direction as to operate the said relay.

The operator now throws her key K' and 45 thereby includes the calling device S in the circuit, instead of the polar relay 10 and the associated windings of the repeating coil.

The operator may now manipulate her calling device S in accordance with the first 50 digit of the desired number, whereupon the selector D operates in the usual manner to raise its wipers to the desired level and rotate them to pick out an idle trunk line. We shall assume that the trunk line terminating 55 in the bank contacts 26 to 28, inclusive, is the first one found idle, and consequently the one selected. That being the case, the connection is extended by way of trunk conductors 29 and 31, upper and lower left 60 windings of repeating coil T, conductors 78 and 79, normally closed contacts controlled by armatures 57 and 59, armature 61 and its resting contact and normally closed contacts controlled by armature 62, conductors 73 65 and 76, and the resting contact of armature 117 and said armature to the upper and lower windings of line relay 100 of the transmission selector E. The line and release relays 100 and 101 of the said selector immediately energize and the latter, at armature 109, places ground on release trunk conductor 30 so as to hold the selector E in its operated position. As a further result of the energization of release relay 101 it prepares the switch for operation at armature 111 and places ground on conductor 74 at armature 110, thereby closing a circuit for the lower winding of electro polarized relay 33. This winding alone, however, consisting of a small number of turns of high 70 resistance, is not able to operate the said relay.

The operator may now operate her calling device in accordance with the second digit of the desired number, thereby interrupting 85 the circuit of the line relay 100 of selector E a corresponding number of times. Each time line relay 100 deenergizes it closes, at armature 107, the following circuit for the vertical magnet 125: from ground by way 90 of armature 107 and its resting contact, armature 111 and its working contact, armature 122 and its resting contact, slow acting series relay 102, and vertical magnet 125 to battery. By the operation of the vertical magnet, the switch shaft and wipers are raised step by step until the latter stand opposite the desired level of bank contacts. Relay 102 energizes in series with the vertical magnet and being slow acting retains 95 its armature attracted throughout the vertical movement. Upon energizing, relay 102 closes the following circuit: from grounded conductor 74 by way of the working contact of armature 112, contact 127, and the lower winding of the ring cut off relay 37 to battery. Upon energizing, relay 37 locks itself to conductor 74 at armature 65 and opens at armature 64 and 66 the connection 100 to the upper winding of the said relay and to the intermittent generator lead. Returning now to relay 102, as a further result of its operation, it closes, upon the closure of the vertical off normal springs, a circuit for the stepping relay 103. Stepping relay 103, 105 upon energizing, closes at armature 116, a locking circuit for itself including armature 119 and its resting contact, and the resting contact of the armature of rotary magnet 126 and the said armature; and, at armature 115, prepares the circuit of the rotary magnet 126. At the end of the vertical movement, slow acting relay 102 deenergizes and closes a circuit for the rotary magnet 126. 110 Rotary magnet 126, upon energizing, steps the wipers 130 to 133, inclusive, into engagement with the first set of bank contacts in the level opposite which they are raised. The rotary magnet also breaks the circuit 115 of the stepping relay 103 which deenergizes 120 125 130

and breaks the circuit of the rotary magnet, whereupon the said magnet deenergizes also and again closes the circuit of the stepping relay. The operation now depends upon whether the test contact with which the test wiper 132 is in engagement is busy or idle. If the test contact is busy it has a ground potential on it, and the stepping relay 103 energizes again and the same cycle of operation is repeated over and over until an idle or undergrounded test contact is reached. When an idle set of contacts is reached, the switching relay 105 energizes in series with the stepping relay 103 over the following circuit: from ground by way of grounded conductor 74, switching relay 105, resting contact of the armature of rotary magnet 126 and said armature, off normal contacts 114, and stepping relay 103 to battery. Relay 103, however, due to its relatively small number of turns and comparatively stiff adjustment, does not energize over this circuit. In the present case, however, we shall assume that the first set of contacts, which are the contacts 134 to 137, inclusive, are idle when the selector is operated as above described. That being the case, the energization of switching relay 105 extends the connection to the trunk line X at armatures 120 and 124 and places ground on the test wiper 132 at armature 123, so as to make the trunk line X busy to the other selectors having access to it, this ground potential extending by way of conductor 143 to multiple test contacts in the banks of the other selectors. As a further result of the energization of switching relay 105, it closes at armature 121 the following circuit: from ground by way of bank contact 135, wiper 131, working contact of armature 121 and said armature, conductor 72, and relay 32 to battery. Relay 32, upon energizing, opens the normally closed bridge around the condenser associated with the right-hand windings of repeating coil T, at armature 50, and at armatures 50 and 51 places the upper and lower windings of battery feed relay 35 in bridge of the said condenser. As a further result of the energization of relay 32, it closes at armature 52 a circuit for reversing relay 34. Relay 34, upon energizing, locks itself to the grounded conductor 74 at armature 60 and at armatures 57 and 59 reverses the conductors 78 and 79 as regards their connection with the windings of line relay 100 of selector E; at the same time introducing the resistances 67 and 68 into the circuit of the said relay. This latter operation is performed merely to decrease the amount of current flowing through the established connection back to the operator. In response to the before mentioned reversal of the connections of conductors 78 and 79, assuming that the operator has returned the

key K' to normal position, the polarized relay 10 in cord circuit O operates its armatures thereby lighting the supervisory lamp L, which apprises the operator of the fact that the call has so far been successful. 70

When the operator is ready to signal the attendant in the private branch exchange, she operates her ringing key on the right hand end of cord circuit O, thereby projecting current out over the established connection to the ringing response relay 36 in the relay group RG, the said relay 36 being connected in bridge of the conductors 78 and 79 by way of the working contact of armature 56 and said armature, and armature 53 and its resting contact. Relay 36, upon energizing, opens, at armature 63, the circuit of ring cut-off relay 37 and the said relay deenergizes. Upon deenergizing, relay 37 closes at armatures 64 and 66 the usual ringing circuit and ringing current is intermittently sent out over the trunk line X. The small capacity condenser 80 which is bridged from armature 66 to its working contact allows enough ringing current to pass through to inform the calling operator that the attendant operator at the private branch exchange is being signalled. 85

The ringing current thus sent out over the trunk line causes the relay 300 of the connector H', which is in bridge of the conductors of the trunk line X, to energize. Upon energizing, relay 300 closes a locking circuit for itself by way of armature 317 and its resting contact, resting contact of armature 316 and the said armature, and armature 311 and its working contact; and, at armature 312, closes the circuit of the answering lamp L' in front of the attendant operator. The attendant operator, upon noting the lighted condition of lamp L', throws the listening key K² thereby operating the springs 224, 225 and 227. Spring 225, upon operating, closes a bridge across conductors 259 and 265 as follows: from conductor 265 by way of spring 225 and its working contact, conductor 264 and relay 301 to conductor 259. 105

In the relay group RG in the main exchange, the closure of this direct current bridge across the conductors of trunk line Z results in the operation of the ring cut-off relay 37. Upon energizing, relay 37 closes a locking circuit for itself at armature 65, and at armatures 64 and 66 removes the intermittent ringing current from the said trunk line and extends, at the said armatures, the connection to the upper and lower windings of the battery feed relay 35. Relay 35 immediately energizes, over the trunk line X and the before mentioned bridge across the said trunk line at the branch exchange, and, upon so doing, closes a local energizing circuit for line relay 100 of selector E at armature 62 and its working 120 125 130

contact, at the same time opening at the normally closed contacts controlled by armature 62 and at armature 61 the connection between conductors 78 and 79 and the said 5 line relay. Accordingly current ceases to flow in the connection extending back to the operator and the polarized relay 10 de-energizes, extinguishing the lamp L. This gives the toll operator answering supervi- 10 sion.

Returning now to relay 301 of connector H', that relay energizes in series with battery feed relay 35 of relay group RG and, upon so doing, closes, at armature 313 and 15 its working contact, a circuit for itself independent of the spring 225 of key K², and at armature 316 opens the locking circuit of ringing response relay 300, allowing the said relay to deenergize and extinguish the 20 answering lamp L'.

The two operators may now converse with each other and the attendant operator, upon learning who the desired subscriber is, finds out the correct number and throws the calling key K³. It will be noted that, with keys K² and K³ both operated, the windings of battery feed impedance 233 are bridged across the conductors of trunk line X. This is done so as to feed talking battery to the 25 called subscriber in case the attendant operator makes a call by way of the connector H' when there is no transmission selector up, on the distant end of the trunk line X. This causes no harm to result in the present case, however, for impedance 233 is so 30 connected that it feeds battery out in parallel with relay 35 of relay group RG. As a further result of the operation of key K³ it closes at spring 229 the circuit of calling 35 device switching relay 220. Upon energizing, relay 220 switches the circuit of the calling device S' from a loop to a grounded circuit. As a still further result of the operation of key K³, it closes at spring 232 and 40 its working contact a circuit for the holding lamp L³, and the said lamp accordingly becomes lighted. A branch of the circuit of lamp L³ extends by way of conductor 282 to battery through release relay 302 of the 45 connector H'. Release relay 302, upon energizing, closes, at armature 315 and its working contact, a multiple point in the circuit of relay 301, closes at armature 317 and its working contact a circuit for the 50 supervisory lamp L² by way of armature 323 and its resting contact, and conductor 261; opens a point in the circuit of release magnet 338, at armature 318, and at the 55 said armature and its working contact prepares an energizing circuit for the switching relay 310 and a locking circuit for the 60 busy relay 308; and at armature 319 and its working contact completes the following circuit for the impulsive relay 303: 65 from ground by way of armature 221 of

relay 220, calling device S', conductor 210, spring 231 and its working contact, conductor 263, armature 319 and its working contact, and impulsive relay 303 to battery. Impulsive relay 303, upon energizing, opens, 70 at armature 320, a point in the circuit of vertical magnet 324 before the said magnet has time to energize and closes at the said armature a multiple point in the circuit of release relay 302. 75

The attendant operator may now operate her calling device S' in accordance with the first local digit of the desired number, thereby producing a number of interruptions in the circuit of impulsive relay 303. In response to the interruptions thus produced, the impulsive relay 303 deenergizes a like number of times, and at each deenergization closes, at armature 320 and its resting contact, the following circuit for the vertical 80 magnet 324: from ground by way of armature 317 and its working contact, armature 320 and its resting contact, vertical off normal springs 329 and 327, slow acting series relay 306, and vertical magnet 324 to battery. By the operation of the vertical magnet, the switch shaft and wipers are raised step by step until the latter stand opposite the desired level of bank contacts which, in this case, is the level in which the line of 85 substation A terminates. Relay 306 is energized in series with the vertical magnet and being slow acting retains its armature attracted throughout the vertical movement and serves to maintain the circuit of the 90 vertical magnet 324 intact after the off normal springs 327-329, inclusive, have shifted; as they do upon the first vertical step. At the end of the vertical movement, relay 306 95 deenergizes and shifts the impulsive circuit 100 from the vertical to the rotary magnet. 105

The attendant operator may now operate the calling device S' in accordance with the next and last digit of the desired number, whereupon a corresponding number of impulses are delivered to the rotary magnet 339 by way of the following circuit: from ground through armature 317 and its working contact, armature 320 and its resting contact, off normal springs 329 and 328, armature 325 and its resting contact, resting contact of armature 334 and said armature, armature 343 and its resting contact, and rotary magnet 339 to battery. By the operation of the rotary magnet the wipers 347-349, inclusive, are rotated step by step until they come to rest on the bank contacts 377-379, inclusive, which are the ones in which the line of substation A terminates. The slow acting relay 309 is energized in multiple with the rotary magnet 339 and opens the circuit of the upper winding of switching relay 310 at armature 336, at the same time completing a circuit from test wiper 348 to the busy test relay 308, and at armature 349 to the 115 120 125 130

ture 337 and its working contact, serves to maintain the circuit of the rotary magnet intact even though the busy relay 308 energizes due to the wiper 348 passing over 5 grounded test contacts.

The operation now depends upon whether the line of substation A is busy or idle. If it is busy there is a ground potential on test contact 378 and the busy test relay 308 10 is accordingly energized. Assuming that such is the case, slow acting relay 309, upon deenergizing, closes, at the normally closed contacts controlled by armature 336, the following locking circuit for relay 308: from 15 ground by way of armature 318 and its working contact, armature 333 and its working contact, normally closed contacts controlled by armature 336, and relay 308 to battery. This locking circuit is closed in 20 order that relay 308 will not deenergize later and allow the connector H' to cut in on the line of substation A after it has become idle. As a further result of the energization of 25 relay 308 it connects, at armature 335 and its working contact, a lead from a busy signalling machine to the lower heavy talking conductor. Since such machines are well known, it has, for the sake of simplicity, 30 been omitted from the drawings. It will suffice to say that by this operation an audible busy signal is sent back to the attendant 35 operator to inform her of the busy condition of the line of substation A. Upon hearing this busy signal, the operator may release the connector H' and try to reach the desired subscriber by calling another nearby substation.

In the present case, however, we may assume that the line of substation A is idle 40 when called. Under these circumstances, when the slow acting relay 309 deenergizes it closes, at armature 336 and its resting contact, the following circuit for the upper winding of switching relay 310: from ground 45 by way of armature 318 and its working contact, armature 333 and its resting contact, upper winding of relay 310, resting contact of armature 336 and said armature, test wiper 348, test-contact 378, private normal conductor 375, switching relay 380 of the line switch C, and stepping magnet 382 to battery. Switching relays 310 and 380 50 energize in series with each other, and the latter clears the line switch C of its normal battery and ground connections at armatures 333 and 385. It may be stated here 55 that, due to a mechanical interlocking device (not shown) between the armatures of relays 380 and 381, the armatures of switching relay 380 are able to operate only about half way at this time and accordingly the wipers of the line switch are not connected up. In the connector H', switching relay 310 energizes, somewhat slowly, owing to 60 65 the retarding effect of the copper slug on

the armature end so as to give the switching relay 380 of the line switch C plenty of time to remove the bridge from the called line, and closes at armature 344 and its working contact, a locking circuit for itself by way 70 of armature 317 and its working contact; grounds the test wiper 348 at armature 242 so as to make the called line busy to the other connectors; and at armatures 340 and 346 completes the connection to the line 75 wipers 347 and 349. The resting contact of armature 332, as indicated by the plus and minus sign, is assumed to be connected to an interrupted generator lead coming from a ringing machine similar to the one shown 80 in Fig. 2. That being the case, ringing current is intermittently sent out to ring the bridged bell at the called substation. The condenser 394 allows just enough ringing current to leak back to inform the calling operator that the called subscriber is being 85 signalled.

When the called subscriber responds by removing his receiver from the switchhook, 90 the ring cut-off relay 307 immediately energizes and closes a locking circuit for itself at armature 331, and at armatures 330 and 332 disconnects the line wipers from the upper winding of the said relay and from the ringing lead and connects them to the conductors 259 and 265 of trunk line X. The supervisory relay 305 immediately energizes and at armature 323 extinguishes the supervisory lamp L², at the same time closing a circuit for relay 304. Relay 304, upon 95 energizing, closes a locking circuit for itself at armature 322, and at armature 321 opens a point in the circuit of relay 301. The attendant operator and the called subscriber now converse with each other, talking battery being supplied to the transmitter at substation A by the low wound battery feed relay 35 of relay group RG in multiple with the before mentioned impedance 233. The attendant operator finds out whether 100 or not the person who answered the telephone is the one wanted and, assuming he is, she appraises the toll operator of the fact and restores the keys K² and K³ to normal 105 thereby removing the impedance coil 233 and relay 301 from in bridge of the conductors of trunk line X. The key K³, upon 110 returning to normal position, opens the circuit of relay 220 at spring 229 allowing it to deenergize; and at the normally closed contacts controlled by spring 231 establishes 115 the following holding circuit for the impulsive relay 303 of the connector H': from ground by way of the release spring 222 and its resting contact, normally closed contacts controlled by spring 231, conductor 263, armature 319 and its working contact, and impulsive relay 303 to battery. It 120 will be noted that the release relay 302 does 125 not have the usual copper slug on it. This, 130

however, does not cause any harm to result for the reason that the said relay is held up over a previously traced circuit while the impulses are being sent and is held up 5 thereafter by the impulsing relay.

- Returning now to the toll operator, when she finds that the called man is on the line she takes whatever steps that may be necessary to connect him with the subscriber who 10 desires to converse with him. To do this she may insert the plug P of the cord circuit O into a suitable jack and from thence extend the connection in any well known or preferred manner. After the connection 15 has been thus extended and the other subscriber has answered, the two subscribers converse with each other as desired, the talking circuits that are shown being outlined by the heavy conductors.
- 20 Ordinarily when a subscriber finishes his conversation with another subscriber he hangs up the receiver, but in the present case, in order to explain an added function of certain parts of the circuits shown in the 25 drawings, we shall assume that the subscriber at substation A fails to replace his receiver upon the switchhook at the end of the conversation. With that condition existing if the toll operator, upon getting the 30 usual disconnect signal from the other subscriber, should remove the plug P' from the jack J the connection will not be released and the attendant operator at the private branch exchange will not be notified, unless 35 certain provisions tending to overcome this difficulty are made. The toll operator, upon receiving a disconnect signal from the other subscriber, and, upon failing to receive the usual disconnect signal from the subscriber 40 at substation A, operates her listening key K so as to ascertain whether or not the subscriber at substation A is still holding the receiver to his ear. Assuming that she tries 45 to talk to him but gets no response, she takes it for granted that he has gone away 50 from his telephone. In order to signal the attendant operator at the private branch exchange, the toll operator operates key K' in such a direction as to project ringing current out over the established connection 55 thereby operating ringing response relay 36 in relay group RG which, upon energizing, unlocks ring cut off relay 37. Ring cut off relay 37, upon deenergizing, projects ringing current out over trunk line X. It will 60 be noted that, since the receiver is off at this time at substation A, the usual energizing circuit is closed for ring cut off relay 37 as soon as it deenergizes. This does not cause 65 it to energize again, however, for the current flow through its upper winding is just sufficient, to operate armature 65 and accordingly is insufficient to operate the more stiffly adjusted armatures 64 and 66. When 70 the toll operator restores her ringing key,

relay 36 deenergizes thereby closing the locking circuit of relay 37 which immediately pulls all the way up and removes the interrupted ringing current from the trunk line X. While relay 37 is in a de- 70 energized condition, the ringing current, in flowing out to the called substation, passes through the low wound supervisory relay 305 in the connector H'. This relay is so adjusted that its armature 323 responds to 75 the ringing current. Each time the armature 323 falls back a circuit is closed over conductor 261 for the supervisory lamp L² and the attendant operator is thereby notified that the toll operator is signalling for 80 her. Upon noting the flickering of supervisory lamp L², the attendant operator throws her listening key and finds out what the toll operator desires and upon learning that the subscriber at substation A has 85 failed to replace his receiver she may operate her release key and release the connector H' in a manner to be described hereinafter.

From the above it will be deduced that, 90 should the subscriber at substation A hang up his receiver and in case the toll operator wishes to call him back to the telephone for some reason, when ringing current is projected out over the connection the bridged 95 bell at substation A is operated in the usual manner. It is obvious that in this case the attendant operator is signalled also. However, she need only throw her listening key and ascertain whether or not the toll operator 100 desires to speak with her, or with the subscriber at substation A.

In the ordinary course of events, when the conversation is completed the subscriber at substation A replaces his receiver upon 105 the switchhook, thereby opening the circuit of battery feed relay 35, in the relay group RG, and supervisory relay 305 of the connector H'. Relay 35 upon deenergizing closes again the previously described circuit for line relay 100 of the selector E, the said circuit extending back by way of conductors 78 and 79 to the toll operator, and at the same time opens the local holding circuit for the said line relay. When 110 this is done current begins to flow again in the toll operator's cord circuit and the polarized relay 10 is accordingly reoperated to light the supervisory lamp L. The toll operator, upon perceiving the disconnect signal, pulls down the connection. When the plug is removed from jack J the circuit of line relay 100 of selector E is broken. Upon deenergizing, line relay 100 opens at 115 armature 107 the circuit of slow acting release relay 101. Upon deenergizing, relay 101 removes ground, at armature 109, from release trunk conductor 30 thereby allowing the intervening selector D to release in the usual manner, at the same time removing 120 125 130

ground from conductor 74 at armature 110 whereupon the following relays deenergize: reversing relay 34 and ring cut off relay 37 of the relay group RG, and switching relay 105 of selector E. Switching relay 105, upon deenergizing, opens, at armature 121, the circuit of relay 32 of relay group RG and the said relay deenergizes. As a further result of the deenergization of release relay 101 it closes at armature 111, a circuit for the release magnet 108 in multiple with relay 104. Relay 104, upon energizing, opens at armature 119 a point in the circuit of stepping relay 103 so as to prevent an accidental operation of the said stepping relay at this time, at the same time closing a locking circuit for itself and for the release magnet 109 in series with the off normal spring 113. As a further result of the energization of relay 104 it opens a point in the test circuit at armature 118, and at armature 117 opens a point in the circuit of line relay 100, to guard against its energization as a result of condenser discharges. By the operation of the release magnet 108 the switch shaft and wipers are restored to normal position, the circuit of the said magnet and relay 104 being opened at off normal spring 113 when the shaft reaches normal position.

In the connector H', supervisory relay 305 upon deenergizing lights the supervisory lamp L², and the attendant operator, upon noticing the lighted condition of the said lamp, throws her listening key so as to make sure that no one is on the line and upon discovering that no one is, she momentarily throws the said key to the opposite position, thereby separating the spring 222 from its resting contact, after which she may restore the said key to normal. Spring 222 upon operating opens the circuit of impulsing relay 303 of connector H' and the said relay accordingly deenergizes and, at armature 320, opens the circuit of release relay 302 which upon deenergizing opens, at armature 319, a point in the circuit of impulsing relay 303. As a further result of the deenergization of release relay 302 it opens at armature 317 the circuit of supervisory lamp L² as well as the locking circuits of relays 307 and 310, whereupon the said lamp becomes extinguished and the said relays deenergize. As a still further result of the deenergization of relay 302 it closes, at armature 318, the circuit of release magnet 338 by way of off normal contacts 326. By the operation of the release magnet the switch shaft and wipers are restored to normal position, the circuit of the release magnet being opened at off normal contacts 326 by the switch shaft when it reaches normal position. The entire connection is now released and the apparatus is ready for another call.

As has been mentioned before, there is usually only one trunk line, such as the trunk line X, extending to the private branch exchange which under ordinary conditions takes care of all toll traffic to the said private branch exchange. As an emergency measure, however, the selector E and other selectors similar to it are given access to a group of regular trunk lines, of which the trunk line Z is one, which as before stated handled the regular traffic to and from the private branch exchange. As is seen in Fig. 3, the trunk line X terminates in the first set of bank contacts in the level in which it is wired, while the trunk line Z terminates in the second set, it being understood that other trunk lines similar to the trunk line Z terminate in the following sets of contacts. Bearing these facts in mind, we shall assume that, in the call just described, the trunk line X is busy, due to its being seized by some other selector similar to the selector E, when the selector E rotates its wipers to find an idle trunk. That being the case the wipers of selector E do not stop on the first set of contacts but rotate automatically to test the succeeding sets. We shall assume further that the trunk line Z is idle at this time. Accordingly, the wipers of the selector E, upon reaching the bank contacts 138 to 141, inclusive, are rotated no further and the switching relay 105, upon energizing, as hereinbefore explained, extends the connection to the said trunk line Z. When the switching relay 105 energizes it closes, at armature 121, a point in the circuit of relay 32 of relay group RG. In the present case, however, the wiper 131 engages an ungrounded contact and accordingly the said relay is not energized.

Upon taking up the operation of switching relay 105 in detail, we find that the said relay, upon energizing, places ground on test contact 140, in the usual manner so as to make the trunk line Z busy to the switches having access to it. It will be noted that this busy potential extends by way of private normal conductor 192 to the test contact 151. By means of the ground potential on test contact 151 and its multiples in the banks of the selectors having access to the repeater F the said repeater and consequently the trunk line Z is made busy to the said selectors. A branch of this circuit extends to battery 120 through the switching relay 176 of the line switch C' and the stepping magnet 175. Switching relay 176, upon energizing, removes, at armatures 178 and 180, the normal battery and ground connections from the trunk line Z at this point. As a still further result of the energization of switching relay 105 the following bridge is placed across the conductors of trunk line Z. From the lower conductor of trunk line Z, by way

of bank contact 141, wiper 133, armature 124 and its working contact, conductor 77, armature 66 and its working contact, lower right winding of repeating coil T, upper winding 5 of electro polarized relay 33, resting contact of armature 50 and said armature, upper right winding of repeating coil T, working contact of armature 64 and said armature, armature 106 and its working contact, working contact of armature 120 and said armature, wiper 130, and bank contact 138, to the upper conductor of trunk line Z. In the private branch exchange the trunk line Z normally extends to the upper and lower 15 windings of line relay 277 of connector H, by way of the release out key, contacts of the call out key, conductors 250 and 258, armatures 292 and 293 and their resting contacts, and the normally closed contacts 20 controlled by armatures 295 and 296. Line relay 277 accordingly energizes. Electropolarized relay 33 included in the circuit of line relay 277 in the relay group RG does not energize at this time, 25 however, owing to the fact that the current flowing through its upper winding opposes that flowing in its lower winding. Returning now to line relay 277, the said relay, upon energizing, closes at armature 296, the 30 following circuit for release relay 278: from ground by way of a pair of normally closed contacts on the blocking key, a pair of normally closed contacts on release in key, conductor 254, armature 298 and its working contact, and release relay 278 to battery. Release relay 278, upon energizing, places 35 ground on release trunk conductor 252, the said ground potential extending back to private normal conductor 211 by way of the resting contact of the upper spring of the release in key, and the said spring. By means of this ground potential on test contact 201 and its multiples in the banks of the switches, in the private branch exchange, 40 having access to the trunk line Z the said trunk line is made busy. A branch of this circuit extends to battery through the busy visual signal 203 which energizes, thereby informing the attendant operator that the 45 trunk line Z is in use.

In order to inform the calling operator that she has obtained connection with a trunk line such as the trunk line Z, there is a tone machine, indicated by the reference 50 characters TM, shown in the lower part of Fig. 3. A lead from this machine is connected to bank contact 139 and also to the corresponding contact in each of the sets of contacts in which a trunk line such as the 55 trunk line Z terminates. This tone machine produces a series of high frequency alternations which flow from ground, by way of the exchange battery, upper winding of the transformer associated with tone machine 60 TM, the associated condenser, bank contact

139, wiper 131, conductor 72, condenser 82, resting contact of armature 58 and said armature, and thence to ground by way of the lower conductor of trunk line Z. A branch of this circuit extends, by way of 70 the right hand windings of the repeating coil T in series, to battery, by way of the upper conductor of the trunk line Z. Hence the operator hears, at this time, a distinctive tone to positively inform her that she has 75 obtained connection with the trunk line Z or a similar trunk line.

The toll operator, upon hearing the tone, is informed thereby that she has obtained 80 connection with a trunk line that is designed to carry regular traffic and has no special provisions for taking care of toll calls. The calling operator may, if she deems it advisable, release the established connection and call again in an attempt to get in on the 85 trunk line X after it has become idle. Assuming that she decides to complete the connection by way of the trunk line Z, she has two courses to follow. She may dial the last two digits herself or she may dial 90 0 thereby signalling the attendant operator and request the latter to complete the connection. We shall assume first, that she decides to follow the former course.

After the toll operator is ready she may 95 operate her calling device in accordance with the first local digit of the desired number whereupon the line relay 100 of selector E deenergizes a corresponding number of times and at armature 106 opens the circuit 100 of line relay 277 upon each deenergization. Each time line relay 277 deenergizes in response to these interruptions produced in its circuit, it closes at armature 298 the following circuit for the vertical magnet 299: 105 from ground by way of the previously traced circuit to armature 298, and thence by way of its resting contact, armature 351 and its working contact, off normal springs 291 and 289, slow acting series relay 279, 110 and vertical magnet 299 to battery. By the operation of the vertical magnet the shaft and wipers are raised step by step until the latter stand opposite the desired level of bank contacts. Slow acting relay 279 energizes in series with the vertical magnet and serves to maintain the circuit of the said magnet intact after the off normal springs have shifted, as they do, upon the first vertical step. At the end of the vertical movement, relay 279 deenergizes and shifts the operating circuit from the vertical to the 120 rotary magnet.

The operator may now operate her calling device in accordance with the next digit 125 of the desired number, whereupon the rotary magnet 286 is operated a corresponding number of times to step the wipers around to the desired set of contacts. The slow acting relay 282 is energized in multi-

ple with the rotary magnet and serves to hold the circuit to the rotary magnet closed in case the busy relay 281 energizes while passing over busy test contacts. In case the 5 called line is busy, the operation of connector H is identical with that already described for connector H'. Accordingly the busy test relay 281 energizes and at armature 360 connects a lead from a busy signaling machine to the lower heavy talking conductor to inform the calling operator that the called line is busy.

In the present case, however, we shall assume that the line of substation A is idle 15 when called. That being the case, slow acting relay 282, upon deenergizing, closes at armature 361, the following circuit: from ground by way of the working contact of armature 350 and the said armature, armature 358 and its resting contact, upper winding of switching relay 283, resting contact of armature 361 and said armature, normally closed contacts controlled by armature 364, test wiper 369, test contact 372, 20 private normal conductor 375, switching relay 380 of the line switch C, and stepping magnet 382 to battery. The two switching relays 283 and 380 energize in series with each other and the latter clears the line 25 switch C of its normal battery and ground connections in the usual manner. In the connector H, relay 283, upon energizing, closes a locking circuit for itself at armature 366, grounds the test wiper 369 at armature 364 so as to make the called line busy 30 to the other connectors; and at armatures 363 and 367 completes the connection to the line wipers 368 and 370. Ringing current is now intermittently sent out in the usual 35 manner to ring the bell at the called substation.

When the called subscriber answers, the ring cut off relay 280 operates and at armature 355 closes the usual locking circuit for 40 itself and at armatures 354 and 357 connects the back bridge relay 276 in bridge of the called line. Back bridge relay 276, upon energizing over the called line, reverses the conductors 250 and 258 of the trunk line Z 45 as regards their connection to the windings of line relay 277. This obviously reverses the direction of the current flow in the upper winding of the electro polarized relay 33 of relay group RG. The two windings of the 50 said relay which heretofore have opposed each other now assist each other in operating the said relay. Upon energizing, relay 33 closes a circuit for reversing relay 34 at armature 55, and the said relay energizes 55 and locks itself to grounded conductor 74 at armature 60; disconnects to distinctive tone from the repeating coil T at armature 58; and, at armatures 57 and 59, reverses the conductors 78 and 79 as regards their 60 connection with the windings of line relay 100

of selector E. As a further result of the energization of relay 33 it closes, at armature 54, a local circuit for the upper winding of battery feed relay 35 in series with resistance 81. Relay 35, upon energizing, 70 closes the previously described local circuit for line relay 100 of selector E, at the same time disconnecting conductors 78 and 79 entirely from the windings of line relay 100, whereupon the current flow in the said conductors ceases and, accordingly the operators' supervisory lamp L is not lighted at 75 this time.

The toll operator may now converse with the subscriber at substation A in the usual 80 manner, and, assuming that the desired subscriber and not some other has answered, she takes the necessary steps to connect the subscriber at substation A with the subscriber who desires connection with him and 85 when such connection is completed the two subscribers may converse with each other.

When the conversation is finished the subscriber at substation A replaces his receiver, thereby opening the circuit of back bridge 90 relay 276 of connector H. Upon deenergizing, back bridge relay 276 lights the supervisory lamp at armature 294. This, however, has no particular function at this time unless the toll operator fails to release 95 the connection. Back bridge relay 276 also reverses the conductors of trunk line Z back to normal, thereby reversing the current flow in them. In the relay group RG, the electropolarized relay 33 responds to this 100 reversal of current by retracting its armatures thereby opening the circuit of relay 35 at armature 54. Upon deenergizing, relay 35 extends the conductors 78 and 79 to the upper and lower windings of line relay 105 100 and at the same time opens the local energizing circuit of the said line relay. When this is done current commences to 110 flow again in the conductors 78 and 79 and the operator is given the usual disconnect signal.

Upon perceiving the disconnect signal, the operator pulls down the connection. When the plug is removed from the jack J, the selectors D and E are released in the 115 usual manner and the circuit of line relay 277 of connector H is opened. Upon deenergizing, line relay 277 opens the circuit of release relay 278. Release relay 278 upon deenergizing closes at armature 352 a circuit 120 for the release magnet 285. Release magnet 285 upon energizing restores the switch shaft and wipers to normal position, its circuit being broken by the off normal contacts 288 when the shaft reaches normal position. All the apparatus used in making the call is now restored to normal.

We shall now consider an alternate method that may be used by the toll operator when she obtains connection with the trunk 125

line Z, or a similar trunk line. Upon hearing the before mentioned tone and being informed thereby as to the nature of the seized trunk, and in case she knows the 5 name of the desired subscriber but does not know his number, the operator may dial the digit 0. Assuming that she does as above noted, the vertical magnet 299 receives ten impulses over the previously 10 traced circuit and accordingly steps the switch shaft and wipers up to the tenth level. Upon reaching the tenth level, the switch shaft operates the spring 287 so as to force it into contact with its working 15 contact. Upon operating, spring 287 closes the following circuit for the answering lamp: from ground by way of armature 352 and its working contact, armature 297 and its resting contact, contact of spring 20 287 and said spring, conductor 256, and the answering lamp to battery, and the said lamp becomes lighted.

Upon noting the lighted condition of the answering lamp, the attendant operator 25 throws her listening key thereby connecting the two conductors 214 and 215 of the operator's head set in multiple with the conductors of trunk line Z, and placing a multiple ground on the release trunk conductor 252 at the lower pair of contacts of the said key, by way of the lower pair of contacts of the release in key, and the lower 30 pair of contacts of the blocking key. As a further result of the operation of the listening key, a circuit is closed for the calling device switching relay 220. Upon energizing, relay 220 closes the following circuit: from ground by way of armature 221 and its working contact, calling device 35 40 S', conductor 210, impulsing relay 205, normally closed contacts controlled by armature 208, a pair of springs on the listening key, conductor 251, armature 361 and its contact, and over previously traced circuit 45 to battery, by way of the rotary magnet 286. Relay 205 energizes over the above traced circuit but neither slow acting relay 282 nor the rotary magnet 286 is able to energize on account of the high resistance 50 of the said relay 205. Upon energizing, relay 205 closes at armature 207 a circuit for slow acting relay 206. Upon energizing, relay 206 completes a local circuit for impulsing relay 205 at armature 208, and at armature 213 prepares the impulsing circuit for 55 the operating magnets of the connector H'. As a still further result of the operation of the listening key, ground from the private normal conductor 211 is placed on conductor 255 at the top pair of contacts of the said key, thereby closing a circuit which extends by way of conductor 255, impedance 284, normally closed contacts controlled by armature 354, and the upper winding of 60 back bridge relay 276 to battery. Upon 65

energizing, relay 276 extinguishes the answering lamp and closes a locking circuit for itself at armature 297 and at armatures 295 and 296 reverses the conductors 250 and 258 as regards their connection with the 70 windings of line relay 277. In response to this reversal, the electropolarized relay 33 of relay group RG energizes with the hereinbefore described results.

The toll operator and the attendant may 75 now converse with each other and after obtaining the desired information from the toll operator, the attendant operator throws her release in key, thereby separating the release trunk conductor 252 from the private 80 normal conductor 211 and placing direct ground on the latter. As a further result of the operation of the release in key, its lower pair of contacts opens a multiple point whereby ground is held on the release trunk 85 conductor 252, and, at another pair of contacts, removes ground from the conductor 254 and consequently armature 298 of line relay 277. Release relay 278 now deenergizes and at armature 350 removes ground 90 from the release trunk conductor 252 so as to unlock any relays in the switch which might be locked at this time, and at armature 352 closes the circuit of the release magnet 285, and the shaft and wipers of connector H are accordingly restored to normal 95 position.

The operator may now return her release in key to normal position, reuniting the private normal conductor 211 and the release 100 trunk conductor 252, and immediately placing ground on the latter and also on conductor 254, thereby closing a circuit for release relay 278. It will be noted now that before release relay 278 energizes that there 105 is a circuit closed from grounded release trunk conductor 252 by way of armature 350 and its resting contact to battery, through cut-off relay 275. This relay, however, having a stiffer adjustment does not energize 110 as quickly as the release relay 278, and consequently the latter relay is able to energize and open the circuit of the cut off relay at armature 350, before the latter energizes, and at the same time places a multiple 115 ground on the release trunk conductor 252.

The circuits are now in readiness for the mechanical operation of connector H and the operator accordingly manipulates her calling device S' in accordance with the first 120 local digit of the desired number, whereupon the impulsing relay 205 is deenergized a corresponding number of times and upon each deenergization completes the following circuit for the vertical magnet 299: from ground by way of armature 207 and its resting contact, armature 213 and its working contact, a pair of springs on the listening or call in key, conductor 251, armature 351 and its working contact, off normal springs 125 130

291 and 289, series relay 279, and vertical magnet 299, to battery. By the operation of the vertical magnet, the switch shaft and wipers are raised step by step in the usual manner until the latter stand opposite the desired level of contacts. In response to the next and last digit of the desired number, the rotary magnet 286 is energized a number of times to step the wipers around 10 to the desired set of contacts, being in this case contacts 371 to 373, inclusive.

When the called subscriber answers, the ring cut off relay 280, upon energizing, removes the intermittent ringing current from 15 the line and connects up the back bridge relay 276 in the usual manner and at the same time opens the previously described locking circuit for the said back bridge relay. The attendant operator and the called subscriber 20 now converse with each other and, after learning that the subscriber who answers the telephone is the one wanted and apprising the toll operator of the fact, the attendant operator restores her listening key, 25 whereupon relays 205 and 206 deenergize. From this point the operation continues as before and consequently does not need to be explained again.

We shall now consider still another variation of an incoming call from the toll operator that might well arise. It sometimes happens that the attendant operator considers it advisable to block all incoming calls, i. e., she throws her blocking key and with 30 the key in this position her answering lamp is lighted as soon as the trunk line Z is seized in the main exchange and the calling operator is unable to operate the connector H owing to the fact that direct ground is 35 removed from the armature of line relay 277 by the operation of the blocking key. A current sufficiently strong to operate the release relay 278, but too weak to operate the vertical magnet 299, is allowed to pass through 40 the resistance 212. Assuming that the blocking key is thrown when a toll call, such as the one previously described, comes in over the trunk line Z, release relay 278, upon energizing, closes at armature 352 the following circuit for the answering lamp: from ground by way of armature 352 and its working contact, armature 297 and its resting contact, armature 356 and its resting contact, conductor 257, the upper pair of contacts of the blocking key, and the answering lamp to battery. The operator, upon noting the lighted condition of the answering lamp, throws her listening key and the call proceeds thereafter in the same manner as 50 previously described except that it is not necessary for her in this case to release the switch as it has not yet been operated.

Attention will now be called again to the trunk line X and its associated equipment in 55 the branch exchange. It sometimes happens

that the attendant operator is forced to be absent, at night for instance, or at other times when there are other persons at the establishment served by the private branch exchange. In this event, one substation, the 70 substation A for example, is set aside for the reception of all toll calls. The attendant operator, before leaving, calls the substation A by way of the connector H' and waits until the subscriber thereat answers. After 75 learning the nature of the call, the subscriber at substation A replaces his receiver. The attendant operator then restores her keys to normal position but does not operate the release key, and accordingly the connection is not released. The trunk line X now extends from the bank contacts 134 and 137 of the selector E in the main exchange straight through to the bridged bell at the substation A, and when a call comes in the said bell is 80 rung in the usual manner, and all the toll calls for the private branch exchange are received thus until the attendant operator returns again.

For the sake of completeness we shall now consider briefly the operation of the equipment in completing regular calls to and from the private branch exchange as well as calls between the various subscribers of the said exchange. Considering first the calls coming in from the main exchange, the bank contacts 150-152, inclusive, associated with the repeater F, Fig. 3, are assumed to be in the banks of a second selector switch in the main exchange. Now when the main exchange subscriber dials two suitable digits, the said second selector is caused to rotate in search of an idle trunk line, such as the trunk line Z. Assuming that the said trunk line is the first one found idle, the before mentioned selector, upon switching through, places a ground potential on test contact 151 immediately and the said ground potential extends by way of private normal conductor 192 to test contact 140 and its multiples in the 100 banks of the toll switches having access to the trunk line Z, thereby making the said trunk line busy. The operation of the switching relay 176 of line switch C' is the same in this case as though the trunk line Z 105 were seized by the selector E. Considering briefly the operation of repeater F, it may be stated that the line relay 155, upon energizing, closes a circuit for release relay 158 which places ground on the private normal conductor 192, at armature 170, before it is removed by the selector which seized the trunk, thereby establishing the usual holding circuit for the said selector. As a further result of the energization of line relay 155 it places a bridge across the conductors of trunk line Z at armature 163, thereby operating the line relay 277 of the connector H in the usual manner. It is obvious that the 110 operation of the said connector will be the 115

same when it is seized by a regular selector as when seized by the toll selector E. Now when the calling subscriber operates his calling device for the next digit the interruptions produced in the circuit of line relay 155 are reproduced in the circuit of line relay 277 of connector H at armature 163. It is thought that with these few remarks the operation of the trunk line Z in connection 10 with an incoming regular call will be sufficiently well understood.

We shall now assume that the subscriber at substation A desires to make a call. When the receiver is removed at substation A a 15 circuit is closed over line conductors 374 and 376 for the line relay 381 of the line switch C. Upon energizing, relay 381 closes at armature 387 a circuit for the switching relay 380 and the stepping magnet 382 in series, 20 and at armature 386 connects the test wiper 389 to a point between the said switching relay and the said stepping magnet. The operation now depends upon whether the test contact, upon which the test wiper 389 25 is standing, is busy or idle. If it is busy there is a ground potential on it, the switching relay 380 is short circuited, and the stepping magnet 382, which interrupts its own circuit, is operated in the manner of a buzzer 30 to advance the wipers 388-390, inclusive in search of an idle trunk line. In the present case, however, we shall assume that the trunk line terminating in bank contacts 391-393, inclusive, is idle. That being the case, 35 switching relay 380 is not short circuited and accordingly energizes. Stepping magnet 382, however, is not energized at this time because of the high resistance of the switching relay. Upon energizing, relay 380 grounds 40 the test wiper 389 at armature 384 and at armature 383 and 385 extends the connection to the trunk line terminating in bank contacts 391, 392 and 393. As has been mentioned before this trunk line is assumed to 45 extend to and terminate in the line relay of a selector connector. Accordingly, the line and release relays of the said selector connector immediately energize and the latter places ground on the release trunk conductor 50 of the seized trunk line before the line relay 381 of line switch C has had time to deenergize. By means of this ground potential on test contact 392 and its multiples in the banks of the line switches, the seized trunk is 55 made busy to the line switches having access to it. This ground potential also extends back by way of armature 384 and its working contact to the switching relay 380 to hold the said relay in its operated position. A 60 branch of this holding circuit extends by way of private normal conductor 375 to multiple test contacts, such as test contacts 372 and 378, in the banks of the connectors thereby guarding the line of substation A against 65 intrusion in the usual manner.

The calling subscriber may now operate his calling device in accordance with the first digit of the desired number whereupon the selector connector, to which the connection has been extended raises its shaft 70 and wipers step by step until the latter stand opposite the desired level of bank contacts.

The operation now depends upon whether the digit called is 0, which is the digit 75 called when a main exchange number is desired, or some other digit. Assuming first that the digit called is some digit other than 0, the circuits, at the end of the vertical movement, are put into condition for 80 the calling of next digit which will cause the switch to operate as a connector to give access to a line in the private branch exchange in the usual manner.

Assuming now that the calling subscriber 85 operated his calling device S² in accordance with the digit 0, the selector connector to which the connection has been extended steps its wipers up to the tenth level and rotates them in search of an idle trunk line 90 leading to the main exchange. We shall assume in the present case that the trunk line Z which terminates in the bank contacts 200 to 202, inclusive, Fig. 5, assumed to be in the bank of the selector connector, 95 is the first one found idle and consequently the one selected. The selector connector accordingly switches through thereby extending a talking connection from the line of substation A to the line contacts 200 and 202 100 trunk line Z, and places a ground potential upon test contact 201 so as to make the seized trunk line busy to the other switches in the private branch exchange having access to it. This ground potential extends by way of 105 private normal conductor 211 to the visual signal 203 and the said signal accordingly becomes operated. A branch of the energizing circuit for the visual signal 203 extends by way of the upper spring of the release in 110 key and its resting contact, release trunk conductor 252, armature 350 and its resting contact, and cut off relay 275 to battery. Relay 275, upon energizing, removes the bridge of the windings of line relay 277 of connector H from the conductors of trunk line Z and connects the said connectors to bank contacts 200 and 202, thereby, finally extending the line of substation A to the conductors of 115 trunk line Z.

When the line of substation A is thus extended the line relay 172 of the line switch C' in the main exchange, is energized and at armature 182 closes a circuit for the 120 switching relay 176 and the stepping magnet 175 in series, at the same time placing ground on the private normal conductor 192 thereby making the trunk line busy to the switches having access to it in the main exchange. The line switch C' is now oper- 125 130

ated in the same manner as described for line switch C and accordingly rotates its wipers in search of an idle trunk line. The trunk lines terminating in the bank contacts 5 of line switch C' are assumed to be connected at the other end to first selector switches. That being the case, the line switch C', upon operating, gives access to a first selector switch, and the line and release relays of 10 the said selector immediately energize and prepare the switch for operation in the usual manner, at the same time placing ground on the release trunk conductor to establish the usual holding circuits for the 15 line switch C' and to maintain the trunk line Z busy. From this point the operation is old and need not be considered.

Having described my invention, what I consider to be new and desire to have protected by Letters Patent will be pointed out 20 in the appended claims.

What I claim as my invention is:

1. In a telephone system, main and branch exchanges, a group of trunk lines 25 connecting said exchanges for use in handling regular interexchange connections, a toll trunk line connecting said exchanges for use only in connecting toll lines with lines in the branch exchange, and toll selectors in the main exchange responsive to a particular digit for connecting with said toll trunk, and responsive to the same digit for connecting with an idle trunk in said group in case the said toll trunk is busy.
2. In a telephone system, main and branch exchanges, a group of trunk lines connecting said exchanges for use in handling regular interexchange connections, a toll trunk line connecting said exchanges 40 for use only in connecting toll lines with lines in the branch exchange, and toll selectors in the main exchange having bank contact sets arranged in groups, the said toll trunk being terminated in the first set of 45 bank contacts in a certain group, while the said first mentioned trunk lines are terminated in the other sets of contacts in the same group.

3. In a telephone system, a selector switch 50 controllable by an operator, two groups of trunk lines accessible to said selector, the trunk lines of the first group having preference over the trunk lines of the other group independent of control by the operator, and 55 means for giving the operator a distinctive signal whenever a trunk line of the second group is selected, said means comprising a special test wiper in said switch and a signalling circuit completed over said wiper.
- 60 4. In a telephone system, main and branch exchanges, a toll trunk line connecting said exchanges, a toll selector in the main exchange controllable by a toll operator for connecting with said trunk line, a plurality 65 of other trunk lines connecting the main and

branch exchanges which are accessible to said toll selector only when the said toll trunk is busy, subscribers' selectors having access to said other trunk lines but not to said toll trunk, and means for giving the toll operator a signal to notify her when one of said other trunk lines is selected in place of the toll trunk, said signalling means being inoperative in case one of said other trunk lines is seized by a subscriber's selector.

5. In a telephone system, main and branch exchanges, a toll trunk line connecting said exchanges, a toll selector in the main exchange controllable by a toll operator for connecting with said trunk line, a plurality 70 of other trunk lines connecting the main and branch exchanges which are accessible to said toll selector only when the said toll trunk is busy, and means for transmitting a distinctive audible tone to the toll operator whenever one of said other trunk lines is connected with in place of the said toll trunk.

6. In a telephone system, main and branch exchanges, a toll trunk line connecting said exchanges, a toll selector in the main exchange controllable by a toll operator for connecting with said trunk line, a plurality 75 of other trunk lines connecting the main and branch exchanges which are accessible to said toll selector only when the said toll trunk is busy, means for transmitting a distinctive audible tone to the toll operator whenever one of said other trunk lines is connected with in place of the said toll trunk, means for extending the connection to a called line, and means for disconnecting the tone during conversation.

7. In a telephone system, main and branch exchanges, a toll trunk line connecting said exchanges, a toll selector in the main exchange controllable by a toll operator for connecting with said trunk line, a plurality 80 of other trunk lines connecting the main and branch exchanges which are accessible to said toll selector only when the said toll trunk is busy, incoming connector switches in which the said trunk lines terminate at the branch exchange, an operator's position at the branch exchange, and circuit arrangements such that the branch operator is required to operate the associated incoming connector in case the said toll trunk is taken for use by the toll operator, while if one of said other trunk lines is connected with the toll operator can operate the associated incoming connector herself.

8. In a telephone system, main and branch exchanges, a toll trunk line connecting said exchanges, a toll selector in the main exchange controllable by a toll operator for connecting with said trunk line, a plurality 85 of other trunk lines connecting the main and branch exchanges which are accessible to said toll selector only when the said toll

trunk is busy, an operator's position at the branch exchange, and circuit arrangements such that the toll operator can signal the branch operator direct over the said toll 5 trunk by ringing thereover, whereas in case one of said other trunk lines is taken for use the toll operator is required to call another digit to signal the branch operator.

9. In a telephone system, main and branch 10 exchanges, a toll trunk line connecting said exchanges, a toll selector in the main exchange controllable by a toll operator for connecting with said trunk line, a plurality of other trunk lines connecting the main and 15 branch exchanges which are accessible to said toll selector only when the said toll trunk is busy, a supervisory signal at the toll operator's position, and means for actuating said signal during the establishment 20 of a connection to the branch exchange only in case the connection is established by way of said toll trunk.

10. In a telephone system, main and branch 25 exchanges, a toll trunk line connecting said exchanges, a toll selector in the main exchange controllable by a toll operator for connecting with said trunk line, a plurality of other trunk lines connecting the main and branch exchanges which are accessible to 30 said toll selector only when the said toll trunk is busy, a supervisory lamp at the toll operator's position, means for lighting said lamp during the establishment of a connection to a branch exchange subscriber and 35 also when such subscriber hangs up, provided the connection is established by way of said toll trunk, and circuit arrangements such that if the connection is established by 40 way of one of said other trunks the said lamp is lighted only when the called subscriber hangs up.

11. In a telephone system, means including 45 an operator's cord circuit and a series of automatic switches for extending a connection to a called subscriber's line, a supervisory lamp at said cord circuit, means for preventing the lighting of said lamp by holding its circuit open during the establishment 50 of the connection and during conversation, and means for lighting said lamp by closing its circuit when the called subscriber hangs up to give the operator a disconnect signal.

12. In a telephone system, means including 55 an operator's cord circuit and a trunk line for extending a connection to a called subscriber's line, a polarized relay in said cord circuit controlling a supervisory lamp, said relay being irresponsible to normal current flow over said trunk line, means for reversing the direction of current flow in said trunk line when the called subscriber answers, means for interrupting the flow of current in said trunk line at the same time 60 so as to prevent the operation of said relay,

and means for reestablishing the flow of current over said trunk line in the reverse direction when the called subscriber hangs up, whereupon said relay is operated to light said lamp. 70

13. In a telephone system, an automatic switch, operating magnets for said switch, relays in said switch for controlling said magnets, a line circuit over which said switch is operable from one point through 75 the medium of said relays, and a second circuit over which current impulses may be transmitted direct to said magnets from another point to operate said switch independent of said relays. 80

14. In a telephone system, two exchanges, an automatic progressively movable switch in one exchange, operating magnets for said switch, an operator's position in each exchange from which said switch may be controlled, a circuit arrangement including relays in said switch whereby the operator in one exchange can control said magnets, and a circuit arrangement for controlling said magnets direct from the operator's position in the other exchange without any intervening relays. 85

15. In a telephone system, a group of automatic switches, operating magnets in each switch, a fast and slow relay combination 95 in each switch for controlling the associated operating magnets, and a fast and slow relay combination common to all of said switches and adapted to be used to control the operating magnets of any one 100 of said switches in place of the relay combination normally assigned thereto.

16. In a telephone system, a group of automatic switches, operating magnets in each switch, a fast and slow relay combination 105 in each switch for controlling the associated operating magnets, a fast and slow relay combination common to all of said switches and adapted to be used to control the operating magnets of any one of said 110 switches in place of the relay combination normally assigned thereto, and a plurality of keys for actuation by an operator to associate the said common relay combination with desired ones of said switches at 115 will.

17. In an automatic telephone system, an automatic switch, an operating magnet for said switch, a line relay and a release relay jointly controlling said operating magnet, 120 both of said relays being quick acting, a release magnet controlled by said release relay, a circuit for said release relay controlled by said line relay, and another circuit for maintaining said release relay energized 125 during momentary deenergizations of said line relay while the switch is being operated, said other circuit including manually operable contacts at an operator's position.

18. In a telephone system, an automatic 130

selector switch, a line relay controlling the directive movement of said switch, a test wiper controlling the automatic selective movement of said switch, a release magnet and a circuit for energizing it to release said switch, a relay connected in circuit with said release magnet, and contacts on said relay for opening the circuit of said line relay and for disconnecting said test wiper.

19. In a telephone system, an automatic switch having line wipers and a test wiper, means for extending a connection to said switch, a discriminating device associated with said switch, signalling means associated with said connection, two classes of trunks accessible to said switch, means for operating said switch to seize one of said trunks, means controlled over said test wiper for selectively operating said discriminating device in accordance with the class to which the seized trunk belongs, and means controlled by said device for operating said signalling means one way or the other in accordance with the selective operation of said device.

20. In a telephone system, an automatic switch having line wipers and a test wiper, means for extending a connection to said switch, a discriminating device associated with said switch, signalling means associated with said connection, two classes of trunks accessible to said switch, means for operating said switch to seize one of said trunks, means controlled over said test wiper for selectively operating said discriminating device in accordance with the class to which the seized trunk belongs, means controlled by said device for operating said signalling means one way or the other in accordance with the selective operation of said device, and means also controlled over said test wiper for sending a distinctive tone current back over said line only when the seized trunk is of a particular class.

21. In a telephone system, first and second exchanges, a toll trunk line and another trunk line connecting said exchanges, a subscriber's selector in the first exchange controllable by a calling subscriber to connect with said other trunk line, said toll trunk line being inaccessible at all times to said subscriber's selector, a toll selector in the first exchange controllable by a toll operator to connect with said toll trunk line when it is idle and to connect with said other trunk line only when said toll trunk line is busy, and means for giving the toll operator a distinctive signal when said toll selector connects with said other trunk line.

22. In a telephone system, first and second exchanges, a toll trunk line and another trunk line connecting said exchanges, a subscriber's selector in the first exchange controllable by a calling subscriber to connect with said other trunk line, said toll trunk

line being inaccessible at all times to said subscriber's selector, a toll selector in the first exchange controllable by a toll operator to connect with said toll trunk line when it is idle and to connect with said other trunk line only when said toll trunk line is busy, means for giving the toll operator a distinctive signal when said toll selector connects with said other trunk line, the last named means being inoperative when said trunk line is connected with by said subscriber's selector.

23. In a telephone system, main and branch exchanges, a group of trunk lines connecting said exchanges for use in handling regular interexchange connections, a toll trunk line connecting said exchanges for use only in connecting toll lines with lines in the branch exchange, toll selectors in the main exchange responsive to a particular digit for connecting with said toll trunk, and responsive to the same digit for connecting with an idle trunk in said group in case the said toll trunk is busy, and means for giving the calling toll operator a distinctive signal when a toll selector connects with a trunk line of said group.

24. In a telephone system, an automatic switch for use in connecting a calling and a called line, a controlling line relay for said switch, operating magnets and a release magnet under control of said line relay, a second relay for opening the circuit of said line relay, and means for energizing said second relay whenever the said release magnet is energized.

25. In a telephone system, an automatic switch for use in connecting a calling and a called line, a controlling line relay for said switch, operating magnets and a release magnet under control of said line relay, an auxiliary stepping relay also controlling one of said operating magnets, a circuit for said stepping relay, a third relay for opening said circuit, and means for energizing said third relay whenever the said release magnet is energized.

26. In a telephone system, a trunk line including talking conductors and another conductor, means including an automatic switch and a second trunk line accessible thereto for extending a connection from the first trunk line to a called line, circuit arrangements in the first trunk line normally in condition for sending impulses to operate said switch, means in said switch for seizing the second trunk line after said switch has been brought into a position corresponding thereto, and means individual to the first trunk line and controlled through said switch over said other conductor responsive to the operation of said seizing means for changing the said circuit arrangements from impulse sending condition to talking condition.

27. In a telephone system, a trunk line, means including an automatic switch and a second trunk line accessible thereto for extending a connection from the first trunk line to a called line, circuit arrangements in the first trunk line normally in condition for sending impulses to operate said switch, means in said switch for seizing the second trunk line after the switch has been brought into correspondence therewith a relay individual to said trunk line for changing the circuits thereof to adapt the same for conditions existing during conversation rather than sending impulses, and means for operating said relay over a circuit path including said switch and independent of the talking conductors responsive to the operation of said switch. 50
28. In a telephone system, a trunk line, other trunk lines of different classes, means for setting up a connection including the first named trunk line and any one of said other trunk lines to a called line, circuit connections individual to said trunk line for use in connection with one of said other trunk lines of a given class, other circuit connections for use with one of said other trunk lines of a different class, means automatically effective for bringing into play the one of said circuit connections corresponding to the class of the particular other trunk line through which a connection is set up, and means controlled by the last named means for informing the calling party of the class of the trunk line to which the first trunk line is connected. 55
29. In a telephone system, a first trunk line, a second trunk line of a given class, a third trunk line of a class different from the class of the second trunk line, automatic switching means for setting up a connection including the first and second trunk lines if the second trunk line is idle and automatically effective for including the third trunk line instead of the second if the second trunk line is busy, circuit connections individual to the first trunk line for use in connection with the second trunk line, other circuit connections individual to the first trunk line for use in connection with the third trunk line, 60 and other means individual to the first trunk line automatically operated responsive to the extension of a connection to said third trunk line for switching from the first circuit connection to the second. 65
30. In a telephone system, a trunk line, two groups of trunk lines, one group being of one class and the other group being of another class, means including automatic switching mechanism for setting up telephone connections including the first named trunk line and any trunk line in one of said groups, testing means associated with said mechanism for causing said mechanism to include a trunk line in the other of said groups instead of a trunk line in said one group responsive to a busy condition in said one group, the first named trunk line being normally in condition to cooperate with a trunk line in the first group, and means 70 automatically operated in case a connection includes a trunk line of the second named group for changing the condition of the first named trunk line to cooperate with a trunk line in the second group. 75
31. In a telephone system, a calling trunk line, other trunk lines divided into two different classes, an automatic switch controlled over said calling trunk line to extend a connection to any one of said other trunk lines, the circuit arrangements being such that the same directive control over said switch may result in the extension of a connection to a trunk line of either class, circuit conditions associated with the calling trunk line for use 80 in connection with a trunk line of the first class, other circuit conditions associated with the calling trunk line for use in connection with a trunk line of the other class, and means for automatically associating the 85 proper circuit connections with the calling trunk line regardless of the class of the other trunk line to which the connection is completed. 90
